UNITED STATES PATENT OFFICE

2,098,251

SHOE SEWING MACHINE

Bernard T. Leveque, Wenham, Mass., assignor to United Shoe Machinery Corporation, Paterson, N. J., a corporation of New Jersey

Original application March 12, 1935, Serial No. 10,621. Divided and this application May 13, 1936, Serial No. 79,281

13 Claims. (Cl. 112—220)

The present invention relates primarily to shoe sewing machines, and is herein disclosed as embodied in a curved hook needle lockstitch machine adapted to sew the outsole to the welt and upper of a welted shoe, the illustrative embodiment of the invention being of the same construction and operation as that of the machine described in applicant's pending application Serial No. 10,621, filed March 12, 1935, of which the present application is a division.

The objects of the invention are to provide in an outsole stitching machine constructions and arrangements of parts capable of high speed operation which will be strong and durable and which can be brought to rest in the desired position quickly and accurately without injurious shock or jar.

With the above objects in view, a feature of the present invention contemplates the provision in an outsole sewing machine of separate trains of mechanism between the cam shaft for the machine and the principal thread manipulating and work feeding devices comprising elements adapted to be disconnected so as to permit said devices to be brought to rest at a predetermined time in the cycle of operations while the cam shaft continues to rotate during the time required to bring it to rest without injurious shock or jar. For stopping the machine, a treadle and suitable connections are provided for disconnecting the cam shaft from its driving means, and treadle operated connections are also provided for disconnecting the elements above referred to so that the thread manipulating and work feeding devices may be brought to rest independently of the rotation of the shaft. In the machine hereinafter specifically described, this feature of the invention is embodied in an element which may be termed "a controller" which is actuated upon stopping the machine to move the movable elements of the actuating trains of mechanism so as to disconnect the thread manipulating and work feeding devices from the cam shaft and, upon starting the machine, is actuated to reconnect said devices and the cam shaft. To actuate the controller to cause the thread manipulating and work feeding devices to be disconnected when the various devices are in the desired stopping position, and also to enable these devices to be reconnected at the proper point in the rotation of the cam shaft when the machine is again started into operation, timing cams on the cam shaft are provided and suitable connections whereby these cams are controlled from the starting and stopping treadle.

Although the devices, combinations and arrangements of parts above referred to relating to the means for disconnecting certain of the operating parts from the cam shaft upon stopping the machine are particularly adapted for use in outsole shoe sewing machines, they are capable of use in other types of machines and, accordingly, the several features of the invention are not to be considered as limited to any particular application except as specifically defined in the claims. 10 Certain features of the present invention also consist in novel and improved devices, combinations and arrangements of parts hereinafter described and claimed, the advantages of which will be obvious to those skilled in the art from the following description.

An outsole shoe sewing machine embodying the several features of the present invention is illustrated in the accompanying drawings, in which; Figure 1 is a view in right hand side elevation of the complete machine with the operating parts and supporting brackets removed from the head of the machine; Figure 2 is a view in side elevation of the head of the machine illustrating particularly the parts which have been omitted from Figure 1; Figure 3 is a detail sectional view of the rotary loop taker which is in the form of a shuttle, together with the thread case and bobbin for the locking thread supported therein; Figure 4 is a view in rear elevation of the head of the machine illustrated in Figure 2; Figure 5 is a view in front elevation of the head of the machine illustrated in Figure 2, on a somewhat larger scale; Figure 6 is a detail plan view partly in section of a portion of the head of the machine with the upper portion of the frame and certain of the operating parts removed; Figure 7 is a detail view in side elevation, partly in section, illustrating the work feeding mechanism; Figure 8 is a detail view, in front elevation, partly in section, illustrating the work feeding mechanism and the take-up mechanism for the needle thread; Figure 9 is a detail view illustrating the connection between the feeding mechanism and locking thread pull-off or measuring mechanism; Figure 10 is a detail view illustrating the locking thread pull-off or measuring mechanism on an enlarged scale; Figure 11 is a detail view in side elevation of the sewing devices adjacent the sewing point; Figure 12 is a detail sectional view of the mechanism illustrated in Figure 11; Figure 13 is a detail view in front elevation of the thread finger and looper; Figure 14 is a plan view of the mechanism illustrated in Figure 13, together with the actuating lever for the looper; Figure 15 is a detail sectional 55

view illustrating, in side elevation, the take-up, pull-off and thread lock for the needle thread, together with their actuating and controlling mechanisms; Figure 16 is a detail view of a portion of the mechanism illustrated in Figure 15, but looking in the opposite direction and with the parts in a different position; Figure 17 is a plan view of the parts illustrated in Figure 16; Figure 18 is a detail sectional view illustrating particularly the presser-foot actuating and controlling mechanism; Figure 19 is a plan view of certain of the parts illustrated in Figure 18, and also of certain parts of the stopping mechanism illustrated in Figures 22 and 23; Figure 20 is a detail sectional view of the presser-foot mechanism illustrated in Figure 19, taken on the line 20—20 of said figure, the parts being shown in the position they assume while the machine is at rest; Figure 21 is a view similar to Figure 20 with the parts in the position they assume when the machine is in operation sewing a seam; Figure 22 is a detail sectional view of the stopping mechanism illustrating the parts in the position they assume when the machine is running; Figure 23 is a view similar to Figure 22, taken on the line 23—23 of Figure 24, illustrating the parts in the position they assume while the machine is stopped; and Figure 24 is a detail sectional view of the stopping mechanism and certain other parts of the machine taken on the line 24—24 of Figure 23.

The work feeding mechanism illustrated in the drawings is of that type in which the work is fed intermittently by the cooperating action of a work support and presser foot constructed and arranged to engage respectively the welt and outsole of a shoe. Referring particularly to Figures 7 to 9, the work support is indicated at 2 and the presser foot at 4, both of these parts being mounted upon a feed carriage in the form of a slide 6 mounted for advancing and retracting movements in the line of feed on fixed guides 8 and 10. The work support 2 is rigidly secured to an arm projecting forwardly from the slide 6 and the presser foot is secured to the forwardly extending arm of a presser foot lever 12 pivotally mounted upon the slide 6. The lever 12 is connected to the cam shaft of the machine through mechanism hereinafter described, by which the lever is actuated to cause the work to be gripped between the presser foot 4 and the work support 2 and to be released during each stitch forming cycle of the machine. The feed slide 6 is advanced and retracted in the line of feed during each stitch forming cycle by the mechanism described and claimed in applicant's pending application Serial No. 10,621, above referred to, and these movements are timed with relation to the movements of the presser foot lever 12, so that the advancing movement to feed the work takes place while the work is clamped, and the retracting movement takes place while the work is released. The work is thus fed past the stitch forming devices, of which the awl and curved hook needle are indicated respectively at 14 and 16.

For imparting the advancing and retracting movements in the line of feed to the feed carriage 6, a toggle is provided comprising the members 18 and 20. These members are connected by the central pivotal joint 22. The member 18 is pivotally connected at 24 to the feed slide 6, and the member 20 is pivotally connected at 26 to a support 28. The pivotal centers 24, 22 and 26 are so arranged that when these centers are in line, the feed slide 6 is at the extreme limit of its ad-

vancing feeding movement. The feed slide is actuated by reciprocating the central joint 22 of the toggle and to this end the member 18 of the toggle is connected by means of a link 30 to the upper end of a pivotally mounted supporting arm 32 which is actuated from the cam shaft of the machine through connections including a link 34 also connected to the upper end of the arm 32.

The curved awl 14 and the curved hook needle 16 are clamped respectively in the awl segment 36 and the needle segment 38, which segments are mounted to oscillate concentrically upon a fixed stud 40 (see Figs. 11 and 12). The needle guide indicated at 42 is secured to a hub interposed between the needle and awl segments, and this hub is also supported from the stud 40. The needle and awl segments are actuated, as hereinafter described, to cause the needle and awl to enter and withdraw from the work. The movements of the awl segment tend to move the needle guide through frictional engagement with the hub of the guide and the guide is thus actuated in the desired manner.

In addition to the needle, the thread handling devices acting on the needle thread consist of a needle threading looper, a thread arm for drawing out a bight of thread between the looper and the work, a loop taker in the form of a shuttle for passing a loop of needle thread over the locking thread case, a loop spreader to spread the loop for the loop taker, a take-up, a thread lock and a needle thread pull-off or thread measurer.

The looper comprises a thread eye 44 formed (see Figs. 5, 11, 12, 13 and 14) in the outwardly bent arm of a rod secured so as to be capable of longitudinal adjustment in an axial socket at the upper end of a downwardly and rearwardly extending shaft 46. The shaft 46 is mounted in a fixed bracket 48 and is provided at its lower end with a gear segment 50, meshing with a gear segment 52 at the forward end of an actuating lever 54. This lever is pivotally mounted on the machine frame and is oscillated from the cam shaft of the machine through connections hereinafter described. While the needle is through the work, the looper, in cooperation with the thread arm, is oscillated to carry the thread outside of and across the circle of the needle to thread the needle.

The thread finger, indicated at 56, is secured to the upper end of a lever 58 pivoted at its lower end upon the fixed bracket 48 and arranged to swing in a vertical plane across the upper end of the looper when the looper is in the position indicated in Figures 13 and 14. As the needle makes its work piercing stroke, the thread finger is moved rearwardly across the top of the looper and draws out a bight of thread between the looper and the work. The mechanism for actuating the thread finger will be hereinafter described.

The loop spreader (see Figs. 5, 10 and 11) comprises an arm 60 secured to a block 62 integral with a laterally extending stud 64 journalled in fixed bracket arms 66 and 68 (see particularly Figure 5). The lower end of the loop spreading arm projects slightly across the plane of the needle and when actuated moves from its rearward position forwardly across the path of the needle to engage one side of the needle loop and extend it to a position to be entered by the loop taker. The loop spreader is actuated from the cam shaft of the machine through connections hereinafter described which comprise a lever arm 70 clamped to the supporting stud of the spreader 75

carrying block 62 between the fixed brackets 66, 68.

The loop taker, which takes the spread loop from the needle and loop spreader and passes it over the thread case for the locking thread, is indicated at 72 (see Figs. 3, 10 and 12). This loop taker is in the form of a discoidal rotary shuttle which passes completely through the needle loop. It comprises a hollow cylindrical body closed at its rear end and open at its forward end to receive the cylindrical locking thread case 74. This locking thread case is loosely mounted upon a supporting stud 76 extending forwardly from the rear wall of the shuttle and forming a bearing for the sleeve 78 projecting rearwardly from the rear wall of the thread case. The sleeve 78 forms a bearing for a bobbin 80 on which the locking thread is wound. The locking thread leads from the bobbin through a passage-way 82 in the cylindrical wall of the thread case and then passes diametrically across the outer front face of the thread case along passage-ways formed in a projection 84 at the top of the thread case and a projection or nose 86 at the bottom of the thread case. The shuttle body at its inner and outer ends is provided with beveled surfaces to facilitate the passage of the needle loop over the shuttle, and between these surfaces is provided with a bearing groove engaged by a circular raceway 88 by which the shuttle is supported in the machine. As shown in Figure 12, the raceway 88 is provided with channels 90 through which lubricating oil is supplied to the bearing surfaces of the shuttle. The periphery 35 of the shuttle is interrupted by a recess shaped to receive a shuttle driving arm 92 and to form the loop taking beak 94 and heel 96 (see Figure 10).

During the operation of the machine, the shuttle is rotated continuously in the same direction by shaft 98, which is driven from the cam shaft of the machine through connections hereinafter described. The locking thread case is held from rotation by a retaining arm 100, the lower end 45 of which is provided with a notch engaging the nose 86 at the bottom edge of the case. To provide ready access to the thread case, the retaining arm 100 is pivotally mounted on the frame of the machine near its upper end by means of a pivot shaft 102 so that the lower end of the retaining arm may be swung outwardly away from the thread case, as indicated in dotted lines in Figure 2. The retaining arm is normally held in retaining position in front of the thread case 55 by means of a pivotally mounted latch 104 arranged to engage a projecting pin 106 at the upper end of the retaining arm above the pivot shaft 102. A spring 108 stretched between the latch 104 and the upper end of the arm 100 serves to retain the latch in engagement with the pin 106 until the latch is raised by the operator when the spring acts to swing the retaining arm away from the thread case.

After the needle loop is carried over the top of the shuttle, it is pulled down from the shuttle and into the work by the take-up mechanism illustrated particularly in Figures 8, 15, 16 and 17. This take-up mechanism comprises two arms 110 and 112 pivotally mounted one above the other to swing in substantially the same vertical plane. At their outer ends these arms carry respectively take-up rolls 114 and 116 over which the needle thread passes in its travel from the source of supply to the looper. In taking up the thread, 70 the take-up rolls 114 and 116 cooperate with fixed

guide rolls 118 and 120, these guide rolls being arranged so that the thread coming from the supply passes first around the roll 118, then over the upper take-up roll 114, then over the lower take-up roll 116, then upwardly to the guide roll 120 and from this roll to the looper. The take-up arms 110 and 112 are arranged to move from the position indicated in Figure 16, in which they are substantially horizontal and parallel, to the position indicated in Figure 15, in which they are substantially vertical and in line with each other. In so moving, the arms 110, 112 cause the take-up rolls 114 and 116 to take up the thread simultaneously in two loops and, by reason of the fact that the arms are substantially in alignment at the limit of their taking-up stroke, the amount of thread taken up is always the same, and is not affected by any overthrow of the arms. The take-up arms are actuated from the cam shaft of the machine through mechanism hereinafter described, which mechanism comprises intermeshing gear segments 122 on the hubs of the arms, a gear segment 124 on the hub of the lower arm 112, and a gear segment 126 meshing with the gear segment 124 and carried at the outer end of one arm of a lever 128.

In the operation of the machine illustrated in the drawings, the depth to which the loop of needle thread is drawn into the work by the take-up is determined primarily by a thread measuring and gripping mechanism acting on the locking thread. This locking thread measuring or pull-off mechanism is best illustrated in Figures 5, 9, 10, 11 and 12, and comprises two gripping jaws 130 and 132 arranged to act on the locking thread 30 between the projections 84 and 86 on the face of the thread case. These jaws have a reciprocating movement back and forth along the lead of the thread and the jaw 132 has a movement towards and from the jaw 130 to cause the jaws to grasp 40 and release the thread. To give the jaws these movements, the jaw 130 is mounted rigidly on the lower end of a slide 134 and the jaw 132 is pivotally mounted upon the slide. The jaws 130 and 132 are located directly in front of the thread case and, in order to provide for the removal of the jaws from in front of the thread case so as to permit access to the thread case, the slide 134 upon which the grippers are carried is mounted in the bobbin case retaining arm 100. The slide, 50 together with the gripping jaws, are thus moved away from the thread case with the arm.

To actuate the slide 134, a train of mechanism is provided connecting the slide with the work feed carriage 6. These connections (see particularly Figures 5 and 9) comprise an arm 136 pivotally mounted upon a projection from the thread case retaining arm 100 and provided with a gear segment meshing with a rack at the upper end of the slide 134. An arm 138 is secured to the 60 pivot stud of the arm 136 and is connected by means of a link 140 to the upper end of a lever arm 142. The pivot stud of the arm 142 is journalled in a fixed portion of the machine frame and to this pivot stud is securely clamped a downwardly extending lever arm 144 to the lower end of which is adjustably secured a pivotally mounted block 146 engaging a slot 148 in the feed carriage 6. The link 140 is provided at each end with a universal joint and is in axial alignment with 70 the pivot stud 102 of the thread case retaining arm 100 so that the swinging movement of the retaining arm into and out of operative position is not interfered with.

The movable jaw 132 of the locking thread 75

measuring gripper is in the form of a leaf spring and is secured to the lower end of a lever 150 pivotally mounted on the slide 134, as shown in Figure 10. In order to move the jaw 132 towards 5 and from the jaw 130 the lever 150 is extended upwardly beyond its pivot, and is provided with a roll engaging a vertical slot in a cross slide 152 mounted in the thread case retaining arm 100. As providing a simple and efficient means for 10 reciprocating the slide 152 to open and close the gripper jaws, the slide is provided at one end with a roll 154 which engages a cam groove formed in a block secured to the carrier block 62 of the loop spreader 60.

15 While the locking thread is being pulled into the work by the action of the take-up, the grippers 130, 132 grasp the locking thread with sufficient firmness to determine accurately the location of the thread lock in the work. After the 20 stitch is set, the grippers are moved downwardly by the above-described connections between the slide and the feed carriage to draw from the bobbin an amount of locking thread determined by the length of the stitch. Upon actuation of the 25 loop spreader, the jaws of the gripper release the thread and, while the needle loop is being pulled from the shuttle, retract to the upper limit of their movement. At this point in the operation, the jaws of the gripper close on the locking 30 thread, as indicated in Figure 10, and remain in gripping engagement with the thread while the stitch is being set.

The locking thread measuring and gripping mechanism above described is well adapted to cooperate alone with the take-up in determining the location of the thread lock in the work. The illustrated machine, however, is also provided with a needle thread pull-off or thread measuring mechanism, and with a thread lock to insure the 35 proper handling of the needle thread and to cooperate with the locking thread measuring and gripping mechanism in securing a uniform appearance of the stitches and the desired location of the thread locks without danger of breaking the thread or injuring the work. This needle 40 thread pull-off and locking mechanism is best shown in Figs. 8, 15, 16 and 17. The needle thread pull-off and measuring mechanism comprises a pull-off arm 156 pivotally mounted on the fixed 45 portion of the machine frame and provided, at its lower end, with a thread eye through which the needle thread passes on its way from the supply to the guide roll 118. This pull-off arm cooperates with a thread measuring arm 158 pivotally 50 mounted on a fixed portion of the machine frame and provided at its lower end with an open ended loop through which the eye of the pull-off lever 156 is arranged to pass. The thread measuring arm 158 is connected to the presser-foot mechanism hereinafter described through a connecting link 160, a bell crank 162, and a connecting rod 164 so that the position of the loop portion which 55 cooperates with the eye of the pull-off is determined by the thickness of the work. The pull-off arm 156 is actuated from the cam shaft 65 through connections hereinafter described to carry the thread eye through the slot of the thread measuring arm so as to pull off an amount of thread determined by the position of the thread measuring arm 158, as clearly shown in Fig. 15. This movement of the needle thread pull-off takes 70 place simultaneously with the movement of the take-up in drawing the last needle loop from the shuttle down into the work. At this time in the 75 operation, the needle thread is locked against

movement by a thread locking arm 166 pivotally mounted in the machine frame and provided at its lower end with a surface arranged to press the needle thread against the surface of the guide roll 118 and lock the roll with the thread against 5 movement. During the passage of the needle loop around the shuttle the take-up arms 110 and 112 and the pull-off arm 156 return to the position illustrated in Figure 16 to give up to the shuttle the amount of thread required to enable the loop 10 of needle thread to pass over the shuttle without pulling any more thread from the supply. The thread locking arm 166 is actuated from the cam shaft of the machine, as hereinafter described. 15

The presser-foot actuating mechanism of the illustrated machine is constructed and arranged to hold the presser-foot yieldingly in contact with the work during the backfeed of the feed carriage with the work support and presser-foot, then to 20 force the presser-foot firmly against the work to grip the work between the presser-foot and work support, and to lock the presser-foot firmly in gripping engagement with the work during the work feeding movement of the feed carriage and 25 also during the movement of the needle in reTRACTING from the work. This presser-foot actuating mechanism (see particularly Figures 18 to 21) comprises a Horton clutch, the driving member of which is actuated from the cam shaft of 30 the machine, and the driven member of which is connected to the presser-foot. The driven member of the Horton clutch is indicated at 168 and comprises a ring surrounding a three-arm driving member 170. The driven member 168 is connected to the presser-foot by means of a rod 172 extending from a lug on the member 168 to the upwardly projecting arm of the presser-foot lever 12. To allow for the feeding movement of the carriage upon which the presser-foot lever is 40 mounted, the link is provided at each end with a universal joint, and at the forward end of the link the universal joint is adjustably secured in a slot in the presser-foot lever. A coiled spring 174 connected to the lug on the member 168 tends 45 to move the member in a direction to force the presser-foot against the work with a yielding pressure. The driving member 170 of the clutch is secured to an oscillating shaft 176 and is provided between its arms with recesses in which are 50 located the gripping rolls 178 of the clutch. The bottoms of the recesses are formed as cam surfaces which, as the driving member is rotated in a clockwise direction, as viewed in Figure 20, causes the rolls to be wedged between the driven 55 and driving members so that the members are locked together and the driven member 168 is positively actuated. This movement of the driven member 168 forces the presser-foot firmly against the work so that the work is clamped between the presser-foot and the work support. Upon the return movement of the driving clutch member 170 in a counter-clockwise direction, the rolls 178 are freed from gripping engagement with the two members of the clutch by the action of 60 the spring plungers 180 illustrated in Figure 21 seated in the arms of the driving member and bearing against the rolls. The initial position of the rolls and, consequently, the extent of the clockwise movement imparted to the driven member 168 is determined by a series of stop projections 182 which extend from plates 184 adjustably mounted on a bracket 186 supported on the reduced end of the shaft 176 and rigidly secured to the machine frame. To limit the movement 70 75 75

of the presser-foot towards the work support under the force of the spring 174, and thus avoid possible breakage, of the parts, in case the presser-foot mechanism is actuated with no work in the machine, a spring pressed stop plunger 188 is arranged in the path of a lug 190 projecting from the driven member 168 of the clutch. This spring plunger, while limiting the movement of the presser-foot towards the work support permits a slight movement of the presser-foot actuating and locking mechanism in case the mechanism is operated with no work in the machine. The connecting rod 164 above referred to as a part of the connections between the presser-foot actuating mechanism and the thread measuring arm 158 is connected at its upper end to a lug projecting from the driven member 168 of the clutch.

The shaft 176 to which the driving member 170 of the Horton clutch is secured is oscillated by connections from the cam shaft 192 of the machine through connections which comprise a cam actuated lever 194 (see Fig. 18) which is pivotally mounted on a long supporting shaft 196 extending forwardly of the cam shaft. The lever 194 is provided with two upwardly extending arms, one of which is provided with a cam follower engaging a groove in a cam disk 198 secured to the cam shaft and the other of which is connected by a link 200 to an arm 202 pivotally mounted upon a shaft 204. The arm 202 forms one member of a toggle joint, the upper member 206 of which extends from the pivotal connection of the link 200 and arm 202 to the outer end of an arm 208 secured to the end of the shaft 176 remote from the driving member 170 of the Horton clutch (see Fig. 19). The toggle joint formed by the members 202 and 206 is arranged so that the joint is in straightened condition at the limit of the actuating movement of the driving clutch member so that the toggle joint through the driving and driven members of the Horton clutch positively locks the presser-foot in work clamping position.

An outsole stitching machine necessarily comprises a large number of parts, many of which have an intermittent or irregular movement. These parts, in order to be strong and durable, must be large and heavy. The momentum of these parts, when operated at high speed, is considerable, and renders stopping of the machine without injurious shock or jar extremely difficult. In the illustrated machine which is designed for operation at high speed, the stopping of the operating parts in the desired position to permit removal of the shoe is accomplished by actuating the principal thread manipulating and work feeding devices from the cam shaft through separate trains of mechanism, and by providing in these trains of mechanism, elements adapted to be disconnected, whereby the principal operating devices of the machine can be brought to rest at a predetermined time in the cycle of operations without simultaneously stopping the rotation of the cam shaft and some of the light and uniformly moving parts actuated thereby. In the illustrated machine movably disconnectible elements are provided in the trains of mechanism for actuating the needle and awl, feed mechanism, take-up, needle threading looper, loop spreader and needle thread lock. Also, the locking thread gripping and measuring mechanism is actuated through connections from the work feed mechanism, the needle guide is actuated through connections from the needle

actuating mechanism, and the needle thread pull off is actuated through connections from the take-up actuating mechanism so that these parts are also brought to rest with the other thread handling and work feeding devices. The trains of mechanism between the cam shaft and the spreader, looper, feed carriage, awl, needle and take-up are similar in that each train comprises a lever in engagement with a cam on the shaft and a link movable into and out of engagement with the lever. The cam actuated lever for the spreader is illustrated in side elevation in Fig. 18, and is indicated at 218. This lever and the corresponding levers of the mechanisms for actuating the looper, feed carriage, awl, needle and take-up are pivotally mounted on the supporting shaft 196 which, as above stated, also forms a pivotal support for the presser-foot actuating lever 194. The lever 210 is provided with a cam follower engaging a groove in the disk 212. The position of this cam disk with relation to the other cam disks of the cam shaft 192, is indicated in Figures 4 and 6. The detachable link on the mechanism for actuating the spreader is indicated at 214. This link is arranged in substantially horizontal position and at its forward end is pivotally connected to the lower end of a two arm lever 216, the upper end of which is connected by a link 218 to the arm 70, hereinbefore described as secured to the pivot stud of the carrier for the loop spreader. Near its rear end and on its under side, the link 214 is provided with a notch 220 adapted to engage a pin 222 projecting from the cam actuated lever 210. While the machine is in operation, the notch 220 is in engagement with the pin 222 so that the two parts are positively connected and the spreader is actuated from the cam shaft. The link is held in this position by means of a coil spring 224 stretched between a point on the link and a fixed point on the machine frame. The cam levers and disconnectible links of the trains of mechanism for actuating the looper, feed carriage, awl and needle are shown in plan in Fig. 6. Referring to this figure, and to Figure 4, the cam actuated lever of the looper actuated mechanism is indicated at 226 and the disconnectible link at 228. The cam lever 226 is provided with a follower engaging a groove in the cam disk 212. The cam actuated lever of the mechanism for actuating the feed carriage is indicated at 230 and the disconnectible link at 234. The cam lever 230 is provided with a cam follower engaging a groove in the cam disk 232. The cam levers for actuating the awl and needle are indicated respectively at 234 and 236. The cam lever 234 is provided with a follower engaging a groove in the cam disk 232 and the cam lever 236 is provided with a cam follower engaging a groove in the cam disk 238. The disconnectible links of the awl and needle actuating mechanisms are indicated at 240 and 242. The cam lever and disconnectible link of the mechanism for actuating the take-up appear in plan in Figure 6, and in side elevation in Figure 15. The cam actuated lever is indicated at 244, and the disconnectible link at 246. The cam lever 244 is provided with a cam follower engaging a groove in the cam disk 238.

The connections between the detachable links and the spreader and feed carriage have already been described. To actuate the looper, the forward end of the disconnectible link 228 is pivotally connected to a lever arm 248 pivotally mounted on a supporting pivot shaft 250 (see Fig. 75

18) and the upper end of this arm is connected by a link 252 to the looper actuating lever, 54 (see Figs. 11 and 14) hereinbefore described. To actuate the awl, the link 240 (see Fig. 12) 5 is pivotally connected at its forward end to the downwardly extending arm of a bell crank 254 pivotally mounted in a fixed portion of the machine frame on the supporting shaft 256 and provided at the forward end of its horizontal arm 10 with a gear segment meshing with teeth formed on the awl carrying segment 36. To actuate the needle, the forward end of the link 242 is pivotally connected to the downwardly extending arm of the bell crank 258 pivotally mounted on the shaft 256 beside the bell crank 254 and provided at the forward end of its horizontal arm with a gear segment meshing with teeth on the needle carrying segment 38.

To raise the disconnectible links out of engagement with the cam actuated levers upon stopping the machine, a controller comprising the shaft 204 and a series of arms 262 secured thereto is utilized (see Fig. 15). An arm 262 is associated with each disconnectible link and each arm is 20 provided at its forward end with a block or plate 264 having on its upper side a recess arranged to engage a pin 266 projecting laterally from the rear end of the corresponding disconnectible link. While the machine is in operation, the arms 262 25 are in lowered position, as indicated in dot and dash lines in Fig. 22, with the blocks 264 extending beneath the pins 266 and out of engagement therewith. While the machine is in operation, as has been stated, the disconnectible links are in 30 their lowered position with their notches in actuating engagement with the pins on the cam actuated levers. At a certain point in the revolution of the cam shaft, the shaft 204 is rocked in a clockwise direction, as viewed in Fig. 15, as will be 35 hereinafter explained, and the disconnectible links are raised out of engagement with the cam actuated levers. At this point in the revolution of the cam shaft, the cam actuated levers are stationary, due to the configuration of the cam 40 grooves, and the pins 266 on the disconnectible levers are in position to be engaged by the recesses in the blocks 264. After the disconnectible links are raised from the cam actuated levers, the links are held from movement by the engagement 45 of the pins 266 with the recessed blocks 264, and the actuated parts are brought to rest while the cam shaft 262 is permitted to continue its rotation.

Upon starting the machine, the control shaft 50 204 is rocked in the opposite direction at the point in the revolution of the cam shaft when the projecting pins on the cam-actuated levers are in alignment with the recesses in the disconnectible links. This rocking movement of the 55 control shaft returns the arms 262 to their lowest position and permits the links to actively engage the cam levers. The links are pulled down by their springs corresponding to the spring 224. To insure the downward movement of the links each 60 arm 262 is provided at its forward end with a plate 268 overlying the corresponding pin 266 on the disconnectible lever.

The mechanism for rocking the control shaft 70 204 upon stopping and starting the machine comprises stopping and starting cams formed peripherally on a cam disk 270 (see Figs. 22, 23 and 24). This cam disk is mounted to rotate with the cam shaft, but is movable longitudinally of the shaft to bring either the starting or the stopping 75 cam into operative position with relation with a

starting and stopping lever. The cam disc is moved longitudinally of the cam shaft through connections from the starting and stopping treadle of the machine, as will be hereinafter described. The starting and stopping lever is provided with two arms, one of which is indicated at 272 and may be termed the starting arm and the other of which is indicated at 274 and may be termed the stopping arm. The starting and stopping arms are provided with cam followers 276 and 278, and these cam followers are so located that a longitudinal movement of the starting and stopping cam disk will move one of the cams out of the plane of its follower before the other cam is brought into the plane of its follower. The stopping cam is indicated at 280 and the starting cam at 282.

When the machine is running, the starting and stopping lever is in the position indicated in Figure 22, in which position the stopping cam 20 280 is out of the plane of the cam follower 278. Upon stopping the machine, the starting and stopping cam disk is moved to bring the stopping cam 280 into the plane of the follower 278 and, as the cam shaft approaches the position indicated in Figure 23, the starting and stopping cam lever is moved to the position indicated in Figure 23, in which position it remains until the machine is again started. Upon starting the machine the cam shaft is first connected to its driving means 25 as will be hereinafter described and thereafter the starting and stopping cam disk is moved to bring the starting cam 282 into the plane of the cam follower 276. As the cam shaft approaches a predetermined angular position, the starting and stopping lever is actuated in a clockwise direction, as viewed in Figures 22 and 23, and thereafter, by reason of the connections to the control rock shaft 204, the starting and stopping lever is returned to the position indicated in Figure 22.

The connections between the starting and stopping cam lever and the rock shaft 204 comprise a bell crank 284 mounted upon the frame of the machine, a link 286 connecting the upper end of the arm 274 of the stopping and starting cam lever with one arm of the bell crank and a link 288 connecting the other arm of the bell crank with an arm 290 secured to the shaft 204. The arrangement of these parts is such that when the starting and stopping lever is actuated by the 30 stopping cam, the shaft 204 is rocked in a clockwise direction, as viewed in Figures 22 and 23, to raise the disconnectible links from their actuating cam levers, and as the parts reach the limit of their movement, the toggle joint formed by the horizontal arm of the bell crank 284 and the link 288 becomes straightened and locks the parts in the position indicated in Figure 23. Upon the reverse movement of the starting and stopping cam lever under the influence of the starting cam 282, the shaft 204 is rotated in a counter-clockwise direction, and as soon as the toggle formed by the bell crank 284 and the link 288 is broken, the weight of the arms connected to the shaft 204 continues the rocking movement of the shaft until the parts assume the position indicated in Figure 22. The movements of the parts in both directions are limited by adjustable stop screws 292 arranged to engage the bell crank 284 above and below its pivot.

Upon stopping the machine, the presser-foot is lifted from the work and retained in this position until the machine is again started. To accomplish this result, an arm 294 is mounted upon the rock shaft 204 and extends at its forward end 75

beneath a lug 296 on the rod 164 which is connected to the driven member 168 of the presser foot actuating clutch. To avoid breakage or injury to the parts in case the lug 296 is engaged by the arm 294 while the member 168 is held against movement, the arm 294 is connected to the shaft 204 so as to be capable of a slight yielding movement. To this end the arm 294 is loosely mounted on the shaft 204 and is yielding connected to an arm 298 rigidly secured to the shaft, the yielding connection comprising a coiled spring 300 seated in the arm and tending to force a projection 302 on the arm 294 towards a projection on the arm 298. The extent to which the presser foot can be lifted on stopping the machine is limited by an adjustable stop rod 304 (see Fig. 11) arranged to engage the presser foot lever 12.

As has been stated, the starting and stopping cam disk which actuates the mechanism for disconnecting many of the actuated parts of the machine from the cam shaft is moved longitudinally of the cam shaft through connections from the starting and stopping treadle by which the cam shaft is disconnected from its driving means. These connections comprise a cam shifting arm 306 (see Fig. 24) forked at its lower end to engage a groove in the cam disk 270 and secured at its upper end to a rock shaft 308 mounted in the frame of the machine at right angles to the cam shaft. To the outer end of the shaft 308 is secured a horizontally arranged cross bar 310 (see Fig. 4) one end of which is forked and provided with oppositely disposed stop screws 312 cooperating with a fixed lug 314 on the frame of the machine to limit the movement of the cross bar, and the other end of which is provided with a pivotally mounted block 316 through which the upper end of the treadle rod 318 extends. This block 316 rests upon a collar 320 secured to the treadle rod and is pressed down against the collar by means of a spring 322 coiled around the upper end of the treadle rod and interposed between the block 316 and a collar 324 secured to the rod. Downward movement of the treadle rod thus swings the cross bar 310 to rock the shaft 308 and move the starting and stopping cam disk 270 to starting position and, after the movement of the cross bar is stopped, continued downward movement of the treadle rod is permitted. Upon the return upward movement of the treadle rod, the cross bar 310 is held in the position to which it has been moved by the downward movement of the rod until the collar 320 again contacts with the block 316 when the continued upward movement of the treadle rod actuates the cross bar in the opposite direction to return the starting and stopping cam to stopping position.

The downward movement of the treadle rod after the starting and stopping cam has been moved to starting position is utilized to connect the cam shaft to its driving mechanism and the upward movement of the treadle rod before the starting and stopping cam is shifted to stopping position is utilized to disconnect the cam shaft from its driving mechanism. The cam shaft is driven through intermeshing spiral gears from a cross shaft 326 on which is mounted a loose pulley 328 which is constantly rotated by a belt passing over the pulley and over a pulley 330 driven by a motor 332 in the base of the machine. The pulley 328 is provided with a clutch surface arranged to cooperate with a clutch member 334 mounted to rotate with the shaft 326 and to be moved longitudinally of the shaft into and out

of engagement with the pulley 328. The movable clutch member 334 is actuated from the treadle rod 318 through connections which comprise a bell crank lever 336, the vertical arm of which is forked and engages a ring mounted on the clutch member 334 and the horizontal arm of which extends below a collar 338 on the treadle rod. During the downward movement of the treadle rod 318, the collar 338 engages the bell crank 336 and forces the clutch member 334 firmly into engagement with the driving pulley 328 after the starting and stopping cam 270 on the cam shaft has been moved to starting position. During the first portion of the upward movement of the treadle rod, the collar 338 is lifted from the bell crank 336 and the clutch member 334 is permitted to move out of clutching engagement with the driving pulley, this action taking place before the starting and stopping cam disk 270 is returned to stopping position.

The treadle rod is acted upon by a lifting spring 340 coiled around the rod and interposed between a collar on the rod and a lug on the base of the machine. At its lower end, the treadle rod is connected to the horizontal arm of a bell crank 342, the vertical arm of which is connected by a link 344 to the upwardly extending arm of a treadle lever 346. The upward movement of the treadle rod, when the treadle is released, is limited by an adjustable stop screw 348 arranged to engage the treadle lever 346.

The shuttle is rotated at a uniform speed through connections from the cross shaft 326 (see Figures 12 and 18) comprising a vertical shaft 348 which is driven from the shaft 326 through intermeshing spiral gears 350 and which drives the shaft 98, to which the shuttle driver 92 is secured, through intermeshing spiral gears 352. To provide a slip connection in the mechanism for driving the shuttle, one of the spiral gears 352 is loosely mounted on the shaft 98 and is clutched to the shaft by a toothed clutch member 354 splined on the shaft and held yieldingly in engagement with the spiral gear by a spring 356 coiled around the reduced rear end of the shaft 98 and interposed between the clutch member 354 and nuts on the end of the shaft. The gears through which the shuttle is driven are proportioned to impart two rotations to the shuttle during each rotation of the cam shaft. The driving mechanism for the shuttle is permanently connected to the cam shaft through the shaft 326 so that the shuttle continues to rotate until the cam shaft finally comes to rest.

The mechanism for actuating the thread lock (see Figs. 15, 16 and 17) comprises a cam actuated lever 358 pivotally mounted on the supporting shaft 196 and provided with a cam follower bearing against the periphery of a cam 360 on the cam shaft. The cam follower is held in engagement with the cam by means of a coiled spring 362 stretched between the upper end of the lever and a fixed point on the frame of the machine. Upon the forward end of the horizontal arm of the cam lever 358 is pivotally mounted a bell crank 364, the vertical arm of which is provided with a cam follower engaging a cam groove in an arm 275 projecting from the hub of the starting and stopping lever 272, 274 and the horizontal arm of which is provided with segmental gear teeth meshing with corresponding teeth on the horizontal arm of the thread locking lever 166. With this construction, the thread locking lever 166 is actuated at the proper time during the operation of the machine, but upon stopping the

machine, the locking lever is moved into inoperative position out of contact with the thread guide roll 118 by the action of the cam groove on the bell crank 364 (see Figs. 22 and 23).

5 As has been described, many of the thread handling and work feeding devices of the machine are disconnected from the cam shaft upon stopping the machine. In addition to these devices, the pull-off for the needle thread and the thread finger are also disconnected from the cam shaft upon stopping the machine.

10 To secure this result, the thread finger is actuated from the needle actuating bell crank 258 through a link 366 connecting the lever arm 58 on 15 which the thread finger is mounted to the horizontal arm of the bell crank, as indicated in Fig. 12, and the pull-off for the needle thread is actuated from the lever 128 of the take-up mechanism through a link 368 connecting the upper arm of 20 the lever 128 with the upper end of the pull-off lever 156 (see Figs. 15 and 16).

15 The nature and scope of the present invention having been indicated, and a machine embodying the several features of the invention having been 25 specifically described, what is claimed is:—

1. A machine having, in combination, devices 30 cooperating to perform an operation, a cam shaft, driving means therefor, separate trains of mechanism for actuating said devices from the cam shaft comprising elements movable to disconnect the actuated devices from the shaft, means for disconnecting the cam shaft from its driving means, means comprising a control member for moving said elements, and means for actuating said control member to disconnect the actuated devices from the shaft while permitting continued rotation of the shaft to final stopping position.

2. A machine having, in combination, devices 40 cooperating to perform an operation, a cam shaft, driving means therefor, separate trains of mechanisms for actuating said devices from the cam shaft, each comprising a cam actuated lever and a link connected to the lever, means for disconnecting the cam shaft from its driving means, and means comprising a control member for moving the links into and out of operative position with relation to the levers, and means for actuating the control member upon stopping the machine to move the links out of operative position with relation to the levers to bring the actuated devices to 45 rest, while permitting continued rotation of the shaft to final stopping position.

3. A machine having, in combination, devices 50 cooperating to perform an operation, a cam shaft, driving means therefor, separate trains of mechanism for actuating said devices from the cam shaft comprising elements movable to disconnect the actuated devices from the shaft, means for disconnecting the cam shaft from its driving means to stop the machine, means comprising a control member for moving said elements, and cams under the control of the operator for actuating the control member upon stopping the machine to disconnect the actuated devices from the shaft while permitting continued rotation of the shaft to final stopping position, and for actuating the control member upon starting the machine to connect the actuated devices to the shaft.

4. A machine having, in combination, devices 55 70 cooperating to perform an operation, a cam shaft, driving means therefor, trains of mechanism for actuating said devices from the cam shaft, one at least of said trains comprising elements movable to disconnect an actuated device from the shaft, a treadle, treadle controlled means for disconnect-

ing the cam shaft from its driving means to stop the machine, and a cam directly under the control of the treadle for moving said elements to disconnect the actuated device from the shaft, while permitting continued rotation of the shaft to final 5 stopping position.

5. A machine having, in combination, devices 10 cooperating to perform an operation, a cam shaft, driving means therefor, trains of mechanism for actuating said devices from the cam shaft, one at least of said trains comprising elements relatively movable to disconnect an actuated device from the shaft, a treadle, treadle controlled means for connecting and disconnecting the cam shaft and its driving means to start and stop the machine, 15 and cams directly under the control of the treadle for moving said elements to disconnect the actuated device from the shaft upon stopping the machine, while permitting continued rotation of the shaft to final stopping position and for moving 20 said elements to connect the actuated device and the shaft upon starting the machine.

6. A machine having, in combination, devices 25 cooperating to perform an operation, a cam shaft, driving means therefor, trains of mechanism for actuating said devices from the cam shaft, one at least of said trains comprising elements relatively movable to disconnect an actuated device from the shaft, a treadle, treadle controlled means for disconnecting the cam shaft 30 from its driving means to stop the machine, mechanism for moving said elements to disconnect the actuated device from the shaft upon stopping the machine comprising a cam and cam follower normally out of cooperative relationship, 35 and treadle actuated connections for relatively moving the cam and cam follower into cooperative relationship upon stopping the machine.

7. A machine having, in combination, devices 40 cooperating to perform an operation, a cam shaft, driving means therefor, trains of mechanism for actuating said devices from the cam shaft, one at least of said trains comprising elements relatively movable to disconnect an actuated device from the shaft, a treadle, treadle controlled means for connecting and disconnecting the cam shaft and its driving means to start and stop the machine, mechanism for moving said elements to disconnect the actuated device from the shaft upon stopping the machine and for moving said 45 elements to connect the actuated device to the shaft upon starting the machine comprising cams and cam followers normally out of cooperative relationship, and treadle actuated connections for relatively moving the cams and cam followers into cooperative relationship upon stopping the machine to disconnect the actuated device from the shaft while permitting continued rotation of the shaft to final stopping position and 50 to connect the actuated device and shaft upon starting the machine.

8. A machine having, in combination, devices 55 65 cooperating to perform an operation, a cam shaft, driving means therefor, trains of mechanism for actuating said devices from the cam shaft, one at least of said trains comprising elements relatively movable to disconnect an actuated device from the shaft, means for disconnecting the cam shaft from its driving means to stop the machine, means comprising a control member for moving said elements, cams under the control of the operator and intermediate 70 connections for actuating the control member upon stopping the machine to disconnect the 75

actuated device from the shaft while permitting continued rotation of the shaft to final stopping position and for actuating the control member upon starting the machine to connect the actuated device to the shaft, said connections comprising a toggle for locking the control member in the position to which it is moved by one of said cams.

9. An outsole shoe sewing machine having, in combination, stitch forming and work feeding devices including a curved hook needle, an awl, a work support, a presser-foot, a feed carriage, a cam shaft, separate trains of mechanism for actuating the needle, awl, and feed carriage from the cam shaft, each comprising elements movable to disconnect the actuated device from the cam shaft, means for disconnecting the cam shaft from its driving means, and means for moving said movable elements upon stopping the machine to bring the needle, awl, and feed carriage to rest, while permitting continued rotation of the cam shaft to final stopping position.

10. An outsole shoe sewing machine having, in combination with the stitch forming and work feeding devices, a curved hook needle, an awl, a work support and presser-foot arranged to receive the projecting edge of a shoe sole between them, a cam shaft, separate trains of mechanism for actuating the needle and awl from the cam shaft, each comprising elements movable to disconnect the needle or awl from the cam shaft, means for disconnecting the cam shaft from its driving means to stop the machine, and means for moving said movable elements upon stopping the machine to bring the needle and awl to rest while permitting continued rotation of the cam shaft to final stopping position.

11. A lockstitch outsole shoe sewing machine having, in combination, stitch forming and work feeding devices including a curved hook needle, an awl, a work support, a presser-foot, a feed carriage, a needle threading looper, a loop taker, a loop spreader to present the needle loop to the loop taker and a take-up, a cam shaft, separate trains of mechanisms for actuating from the cam shaft the needle, awl, feed carriage, the looper, take-up and loop spreader, said trains comprising elements movable to disconnect the

actuated devices from the cam shaft, means for disconnecting the cam shaft from its driving means to stop the machine, and means for moving said movable elements upon stopping the machine to bring to rest the devices actuated through said trains, while permitting continued rotation of the cam shaft to final stopping position.

12. A lockstitch outsole shoe sewing machine having, in combination, stitch forming and work feeding devices including a curved hook needle, an awl, a work support, a presser-foot, a feed carriage, a needle threading looper, a thread finger to draw out a bight of thread between the work and the looper, a thread case for the locking thread, a loop taker to pass a loop of thread over the locking thread case, a loop spreader to spread the needle loop for the loop taker, a take-up, a cam shaft, driving means therefor, a plurality of separate trains of mechanism between the shaft and said devices for actuating said devices, certain of said trains comprising elements movable to disconnect the actuated devices from the cam shaft, means for disconnecting the cam shaft from its driving means to stop the machine, means comprising a control member for moving said elements, and means for actuating said control member upon stopping the machine to disconnect a plurality of the actuated devices from the shaft, while permitting continued rotation of the shaft to final stopping position.

13. A shoe sewing machine having, in combination, stitch forming and work feeding devices including a curved hook needle, a needle threading looper, a thread finger to draw out a bight of thread between the work and the looper, a cam shaft, driving means therefor, a train of mechanism between the shaft and the needle for actuating the needle, a connection between said train and the thread finger for actuating the thread finger, means for disconnecting the cam shaft from its driving means to stop the machine, and means for rendering said train of mechanism inoperative upon stopping the machine to bring the needle and thread finger to rest, while permitting continued rotation of the cam shaft to stopping position.

BERNARD T. LEVEQUE.
